UNITED STATES PATENT OFFICE.

AXEL G. BERGMAN, OF NEW YORK, N. Y., ASSIGNOR TO LEYGRAND & COMPANY, INC.,
TRUSTEE, OF NEW YORK, N. Y., A CORPORATION OF NEW JERSEY.

PROCESS AND APPARATUS FOR FORMING CASTS.

1,335,475.

Specification of Letters Patent. Patented Mar. 30, 1920.

Application filed October 15, 1919. Serial No. 330,717.

To all whom it may concern:

Be it known that I, AXEL G. BERGMAN, a subject of the King of Sweden, residing in the borough of Manhattan, city, county, and 5 State of New York, have invented certain new and useful Improvements in Processes and Apparatus for Forming Casts, of which the following is a specification.

This invention relates to a process and 10 apparatus for forming plaster or other similar casts, and is more particularly directed to the formation of a mold or matrix to be used in the construction of artificial limbs.

Artificial limbs are customarily provided 15 with a receiving socket for that part of the limb which is left after the amputation, usually called the stump. Such sockets should, of course, fit the stump accurately, conforming to its contour as closely as possible. In 20 an effort to accomplish this result it has heretofore been proposed to take a plaster cast of the stump and to use this plaster cast as a guide for fashioning the socket of the limb. Such efforts have, however, been 25 only partly successful, since the casts have been taken of the stump by simply immersing it in a solution of plaster of Paris, or similar substance, and permitting the latter to set. This produces a correct matrix of 30 the limb as it normally exists, but fails to take into account the fact that when the leg is used the full weight of the user is borne by the artificial limb in walking, with the result that the stump is put under a pressure 35 which changes its form very materially. Under such pressure the muscular or fatty portions of the limb yield, with the effect that the bony sections are pressed against the socket and continued use becomes painful or impossible.

According to the present invention I provide a process and apparatus for making molds or casts which will conform to the shape of the stump while the latter is under 40 substantially the same pressure as is experienced in use. The result is that the socket of the artificial limb when constructed to conform to the cast thus made perfectly fits the stump under conditions of 45 actual service, so that pain or discomfort in the use of the limb is avoided.

The invention may be practised in several ways, but I prefer for simplicity to adopt a

method which enables the person whose cast is to be taken to himself introduce the necessary pressure. Thus according to the preferred form I provide a receptacle of suitable size and shape in which the plaster of Paris, or other molding material, is introduced in fluid form, and I confine the fluid substance against escape while the stump is introduced within it, the user placing his weight, or a considerable part thereof, onto the stump, so that it is put under a pressure substantially similar to the pressure which 55 it will afterward bear when the artificial limb is worn. The invention includes certain other features of improvement which will hereinafter be more fully described.

Referring to the drawings which illustrate one form of the invention,

Figure 1 is a diametrical section of an appropriate form of receptacle for use in practising the present invention.

Fig. 2 is a diagrammatical view of a limb 75 equipped for the molding operation.

Fig. 3 is a view during the molding operation, the receptacle being shown in diametrical section.

Fig. 4 is a plan view of the form of stock- 80 ing I prefer to employ.

Fig. 5 is a plan of a rubber disk which is useful in practising the invention.

Referring to the drawing, let A indicate a suitable mold receptacle which for 85 the present purpose is best elongated to an extent to receive the longest stump which is designed to be molded. It is preferably tapered inwardly from top to bottom, and is best provided with a lining member B which 90 may consist of a sheet of metal preferably with unattached edges, so that it may be sprung apart upon removal from the receptacle A. It is best to provide a lower lining disk C. Within the metallic lining 95 I prefer to arrange a flexible lining, or bag, which is best made of water-proof material, such as rubber sheeting or suitably prepared paper. The object of this lining is to practically contain the plaster of Paris mixture, 100 thereby avoiding the soiling of the mold proper or adherence of plaster of Paris thereto. The receptacle A is preferably provided with a bead or lip A', both for stiffening purposes and also to provide a shoulder 105 around which the top of the flexible lining D

and other parts to be described may be passed and secured in place by some form of tension member, such as the elastic band G.

5 In illustrating the invention I have chosen a typical case wherein the amputation is between the knee and the foot, and specifically one which is close to the ankle.

10 In Fig. 2 I have shown the stump and limb properly prepared for the casting operation in advance of the immersion of the stump in the molding material. I prefer to incase the stump preferably up to the knee in the form of stocking indicated by the 15 letter F in Fig. 2 and shown attached in Fig. 4. It will be noted from Fig. 4 that the upper part of the stocking F is enlarged to an extent which is out of proportion to the limb for a purpose to be shortly described. Over the stocking and arranged at 20 about the knee is a rubber, or other suitable disk-like sheet, such as is indicated by the reference letter E, and which is shown detached in Fig. 5. The disk E is provided 25 with a central aperture of smaller dimensions than the knee so that it hugs the knee very closely and with considerable tension.

When the stump has been suitably prepared as shown at Fig. 2, the mixture of 30 plaster of Paris, or other molding material, is then made, and in the case of plaster of Paris I prefer to mix the material with water to the consistency of a heavy cream or light batter. The stump is then 35 immersed in the liquid and the edges of the disk E are brought over the top of the receptacle A and fastened down fairly tightly by the use of some tension member, such as the rubber strip H. That part of the 40 stocking which is enlarged and lies above the disk E is then turned downwardly and stretched over the top of the disk and the bead of the receptacle, and is also fastened down by a suitable tension member, such as 45 the rubber strip I.

The person whose cast is to be taken then 50 preferably stands (in case one limb is still intact) and places his weight, or a considerable proportion thereof, on the limb which has been partly amputated. The mold is elevated if necessary by the use of a stool or other support until it is approximately 55 the right height so that when pressure is put upon the stump the user will be substantially erect.

The result of the weight of the user being 60 placed upon the stump is that the latter descends farther into the mold passing from a position which is roughly indicated in dotted lines at L in Fig. 3 to the position shown in full lines. This displaces a considerable 65 quantity of the molding fluid which tends to overflow the mold. This is resisted, however, by the rubber disk E so that the parts assume substantially the position of Fig. 3.

Care should, of course, be taken initially to see that there is sufficient level of the molding fluid to reach the top of the mold, and even beyond, when the weight is placed upon the limb. When the proper pressure is 70 reached it is maintained until the molding fluid hardens and sets.

During the molding operation the pressure of the fluid is applied very evenly to the stump, thus compressing the muscular 75 portions to substantially the extent which they will be compressed in the use of the finished artificial limb. The bony portions of the stump are hence permitted to find their natural place, projecting as they will 80 naturally and forming the proper recesses for themselves in the matrix. As the tension of the fluid is uniform on all parts a very precise and comfortable fit of the subsequently formed socket is assured. 85

The precise degree of weight which is placed upon the stump during the molding operation will differ somewhat with different individuals, but the best results are usually found when all the weight is placed 90 upon the stump which the user can conveniently and comfortably stand. This will usually be considerably over one half the weight of the user and sometimes nearly all the weight. I have found in practice 95 that it is advisable to apply vaseline, or other grease, to the stump before placing it in the stocking and also to dampen the stocking well with water. If any leakage takes place in the plaster of Paris this will 100 soon stop on account of the hardening of the latter. When the plaster of Paris attains some degree of hardness the pressure upon the stump can be relieved, but it should be kept in place until the plaster of Paris 105 has fully hardened.

After the molding operation is completed, care should be taken in removing the stump. It is advisable to gently reduce the pressure, bring the stump into the passive 110 condition and to work the muscles slightly to help introduce air between the stump and the mold. The muscles may be compressed slightly by the finger so as to assist in this operation, whereupon the stump may be easily withdrawn. 115

It will be understood that the specific process may be very considerably varied without departing from the invention so long as the mold is made under pressure, 120 and that the form of apparatus is merely shown as one adapted for the purpose and is susceptible to wide variation.

It will be also understood, of course, that after the matrix is made, a plaster, or other 125 cast, will be taken and that the socket of the artificial leg will be fabricated as a facsimile of the matrix by the use of the replica of the stump obtained by the cast. This can be done by molding papier mâché 130

around the replica of the stump, or by building it up of leather, or in any other suitable way.

What I claim is:—

- 5 1. A process of forming a replica of a stump in the production of artificial limbs, comprising forming a matrix of the stump while the latter is under pressure.
- 10 2. A process of forming a replica of a stump in the production of artificial limbs, comprising forming a matrix of the stump while the latter is under a pressure approximating that which the stump is under in the use of the completed limb.
- 15 3. A process of forming a replica of a stump in the production of artificial limbs, comprising forming a matrix of the stump and during the matrix forming operation placing the stump under a pressure by 20 forcing the latter into the matrix forming fluid.
- 25 4. A process of forming a replica of a stump in the production of artificial limbs, comprising placing the matrix forming fluid in a mold receptacle, introducing the stump therein, pressing inwardly upon the stump and confining the fluid against escape.
- 30 5. A process of forming a replica of a stump in the production of artificial limbs, comprising placing the matrix forming fluid in a mold receptacle, introducing the stump therein, pressing inwardly upon the stump and confining the fluid against escape by 35 a flexible connection between the limb and the top of the receptacle.
- 35 6. An apparatus for making matrices of a stump or the like, comprising a receptacle

for containing the molding material, an opening for the introduction of the stump and means for placing the molding material under pressure.

7. An apparatus for making matrices of a stump or the like, comprising a receptacle for containing the molding material, an opening for the introduction of the stump and means for placing the molding material under pressure, said means comprising a flexible disk through which the stump passes.

8. An apparatus for making matrices of a stump or the like, comprising a receptacle for containing the molding material, and a flexible disk having an aperture through it.

9. An apparatus for making matrices of a stump or the like, comprising a receptacle for containing the molding material, and a flexible lining member within the mold and a flexible disk for the top of the mold having an aperture through it.

10. An apparatus for making matrices of a stump or the like, comprising a receptacle for containing the molding material, a separable metallic lining for said receptacle and a flexible disk for the top of 65 said receptacle.

11. An apparatus for making matrices of a stump or the like, comprising a receptacle for containing the molding material, a separable metallic lining for said receptacle, a flexible lining within said metallic lining 70 and a flexible disk for fitting over the mold.

In witness whereof I have hereunto signed my name.

AXEL G. BERGMAN.
